SUPPORTING BELT

Filed Nov. 7, 1928

Fig. 4

UNITED STATES PATENT OFFICE

JOHN V. MOORE, OF PAWTUCKET, RHODE ISLAND, ASSIGNOR TO MOORE FABRIC COMPANY, OF PAWTUCKET, RHODE ISLAND, A CORPORATION OF RHODE ISLAND

SUPPORTING BELT

Application filed November 7, 1928. Serial No. 317,745.

This invention relates to a belt adapted to be worn around the waist and commonly used for supporting garters or sanitary accessories.

5 One object of my invention is to provide a belt for such purposes which will fit the form of the wearer snugly and without discomfort, and which will retain its desired position without excessive tension.

10 A further object is to provide a construction in which provision is made to prevent the belt from rolling at the edges, preferably by providing fold lines in the belt substantially spaced apart and spaced from the edges 15 of the fabric.

My invention further relates to arrangements and combinations of parts which will be hereinafter described and more particularly pointed out in the appended claims.

20 Preferred forms of the invention are shown in the drawings in which

Fig. 1 is a perspective view showing my invention embodied in a sanitary belt;

Fig. 2 is a similar view showing the invention applied to a hose-supporting or garter belt;

Fig. 3 is an enlarged front elevation of a portion of the fabric;

Fig. 4 is a sectional end elevation, taken 25 along the line 4—4 in Fig. 3;

Fig. 5 is an enlarged detail longitudinal section, taken along the line 5—5 in Fig. 3; and

Fig. 6 is a transverse sectional elevation on an enlarged scale, taken along the line 6—6 30 in Fig. 3.

Referring to the drawings, I have indicated a supporting belt 10 preferably formed of a single piece of elastic fabric, which fabric in the preferred form of my invention is woven curvilinear, as described in my Patent No. 1,770,741.

In Fig. 1 I have shown the belt provided with tabs 11 to which a sanitary napkin may be secured and in Fig. 2 I have shown the belt 10 provided with straps 12 forming parts of hose supporters or to which such supporters may be attached. Obviously the tabs 11 and straps 12 may all be placed on a single 45 combination belt, if so desired.

A very important feature of my present invention lies in the provision of inherent fold lines 15 extending lengthwise of the fabric and spaced substantially apart and substantially inward from the edges of the fabric. These fold lines cause the belt to bend naturally along the fold lines 15, as indicated in Fig. 4, so that as the belt is drawn against the flesh, the edge portions will bend outward, rather than rolling transversely, 55 and when released, the belt will resume its original flat condition.

This provision of inherent fold lines has been found of very great importance, as a belt thus constructed retains its shape during extended usage, whereas without this construction the edge portions tend to roll transversely of the belt, particularly when worn by fleshy persons, and when thus rolled, the belt does not readily return to its original or flat 60 condition and quickly becomes unserviceable.

The fold lines in my improved belt may be formed by any one of numerous variations in weave, one form of which is illustrated in Figs. 3, 5 and 6.

In weaving the fabric therein shown, I provide folding sections 20, preferably having a form of leno weave along each side thereof, and having a substantial width of the fabric at the fold line formed entirely 70 without warp threads, as indicated in Fig. 6.

Furthermore, the filling threads are preferably arranged in spaced groups, as indicated at 21 and 22 in Fig. 5, the groups 21 and 22 alternating at the opposite faces of the fabric and presenting the spaced appearance shown in Fig. 5 when the fabric is under tension.

As no warp threads are present in these fold portions of the fabric, openings of substantial cross section are thus formed in the fabric, into which openings the flesh of the wearer is pressed slightly, when the belt is in use, thus giving the belt a more secure hold and causing the belt to retain its desired position with substantially less belt tension.

While I have described a preferred form of weave for producing the fold line effect, it will be obvious that the fold lines may be 100

produced by many other variations in weave.

Having thus described my invention and the advantages thereof, I do not wish to be limited to the details herein disclosed, otherwise than as set forth in the claims, but what I claim is:—

1. A supporting belt formed of a single thickness of inherently curvilinear elastic fabric having attaching elements secured thereto, said fabric being woven in a single piece with longitudinal extending spaced parallel portions thereof formed deficient in warp threads and providing longitudinally extending fold lines in the belt substantially spaced apart and substantially spaced from the edges of the fabric and from the edges of the finished belt.
2. A supporting belt formed of a single thickness of inherently curvilinear elastic fabric having attaching elements secured thereto, said fabric comprising spaced groups of closely adjacent warp threads and spaced weft threads extending across the spaces longitudinally separating said groups, successive weft threads being alternately adjacent opposite faces of the fabric, the spaces between the groups of warp threads being of substantial width and providing parallel fold lines extending longitudinally of the belt and substantially spaced from the edges of the fabric and of the finished belt.

In testimony whereof I have hereunto affixed my signature.

JOHN V. MOORE.
